United States Patent Office

Des. 182,874
Patented May 27, 1958

182,874

BOAT

Richard C. Bradley, Fort Lauderdale, Fla.

Application September 30, 1957, Serial No. 47,923

Term of patent 14 years

(Cl. D71—1)

Des. 182,874

PAGE 2

FIG. 3

FIG. 4

FIG. 5

FIG. 6

Fig. 1 is a perspective view of a boat, showing my new design.

Figs. 2, 3, 4, 5, and 6 are, respectively, side elevational, top plan, front elevational, bottom plan and rear elevational views of the same.

I claim:

The ornamental design for a boat, as shown.
